UNITED STATES PATENT OFFICE.

JOHN REECE, OF MANCHESTER, MASSACHUSETTS.

DRIVING AND STOPPING MECHANISM.

1,220,786.

Specification of Letters Patent. Patented Mar. 27, 1917.

Application filed September 5, 1916. Serial No. 118,486.

To all whom it may concern:

Be it known that I, JOHN REECE, a citizen of the United States, residing at Manchester, in the county of Essex and State of Massachusetts, have invented certain new and useful Improvements in Driving and Stopping Mechanisms, of which the following is a specification, reference being had therein to the accompanying drawing.

10 This invention relates to driving and stopping mechanisms, and more particularly to a mechanism adapted to be incorporated in power driven machines, in which high or destructive momentum is present by reason 15 of the great weight or speed of the rotating parts.

The main object of the present invention is to effectively provide for the stoppage of the rotating shafts of such a machine so as 20 to give a predetermined final angular position of the shaft, and yet without undue or destructive shock, and to effect this accurate and easy stoppage in a predetermined manner and quickly in point of time.

25 It is a further object hereof to bring about such an advantageous stoppage of the machine in an automatic manner, that is to say, without any special attention or skill on the part of the operator. Further and detailed 30 objects and advantages of the present invention will be elucidated in the hereinafter following description, or will be apparent to those skilled in the art.

To the attainment of the above referred to 35 objects and advantages, the present invention consists in the novel mechanisms, devices, arrangements, details and other features herein shown or described.

I will first describe one form of driving 40 and stopping mechanism embodying the present invention, and will then point out the novel features in the claims.

In the accompanying drawings, Figure 1 is a left elevation partly in generally central 45 section of a portion of a machine containing the driving and stopping mechanism embodying the present invention.

Fig. 2 is a front elevation of the mechanism shown in Fig. 1, with the machine 50 frame or case shown in section to better disclose the interior.

Fig. 3 is a partly sectional view of certain details.

Fig. 4 is a right elevation of the parts constituting the impact stopping device. 55

Fig. 5 is similar to Fig. 4 showing a different stage of operation.

Fig. 6 is a diagram of the control lever or pedal action.

All the figures, excepting Fig. 5, show the 60 parts in their position after the machine has been stopped.

The present invention for stopping a machine operates upon the principle of preventing the application of the stopping device until the decreasing speed of the driven shaft has reached a certain low speed sufficient to carry the parts through by momentum to the final position, but insufficient to produce any substantial shock. Also in its 70 fullest embodiment the invention involves a frictional or analogous retarding means by which the destructive energy and momentum may be quickly eliminated by retarding the shaft speed, the retarding action 75 ceasing when the decreasing speed has reached a predetermined low speed, so that the shaft is left running free under sufficient momentum to carry the parts through without the danger of premature stoppage by 80 the retarding means.

The described operations are preferably automatically controlled by the machine itself through the shaft which is to be stopped, and for this purpose among other devices 85 is embodied herein a governor or speed-operated instrument, which turns in synchronism with the shaft and which assumes different positions or conditions according to the speed. By causing this governor to 90 operate so as to disengage the friction brake or retarding device at a designated low speed and to then permit the stopping device to assume operative condition, the objects of the present invention are secured. 95

Referring first to some of the general parts, the machine is shown as having a hollow base casting 8, which incases parts of the mechanism. Upstanding from the base is a post 9, which may extend to a suitable 100 height for the support of the stitching mechanism or other mechanism which is to be driven and stopped. The base also has an upstanding bracket 10, which supports a bearing for a shaft 11, the post 9 supporting 105 a bearing at the other end of the shaft.

The shaft 11 may be considered one of the driven shafts of the machine, since it is permanently geared to the operating or stitching shaft and rotates and stops with the latter.

Thus, at the front end of the shaft 11 is provided a bevel gear 12, which meshes with a bevel gear 13 carried by a cross shaft 14, suitably journaled in the post 9. The cross shaft extends through the casing or wall of the post, and at its exterior end is provided with a helical gear 15, which is in mesh with a helical gear 16 carried on a shaft 17 that extends upwardly, and is suitably geared to the operating or stitching shaft of the machine.

In order to provide for the application of power to the shaft 11 it is shown as provided with a belt pulley or power pulley 18 turning loosely on the shaft. At this point may be mentioned also the brake or retarding device consisting of a non-rotatable cone member 19 having adjusting screws 20 for adjusting its effectiveness of action. When the power drive is thrown out the brake device comes into action, and before being disengaged is supposed to retard the shaft speed from the full working speed to a fraction thereof, for example, one-fifth full speed, resulting in a reduction of the destructive energy or momentum in the proportion of 25 to 1, so that, when the stopping device finally acts, the energy and impact are negligible.

In order that the shaft 11 may be coupled either to the power pulley 18 or to the brake cone 19, a clutch device 25 is provided. This may comprise a clutch part or disk 26 adapted to engage frictionally with a corresponding portion of the driving pulley 18; also a clutch part or cone 27 adapted to engage in the brake cone 19. The clutch has a sleeve portion 28 splined to the shaft 11 enabling it to be shifted axially to cause one or the other of the clutches to be engaged.

For shifting the clutch 25 a ring 29 is arranged loosely in a suitable groove in the clutch sleeve 28, and the ring is engaged by the upper end of a yoked lever 30, which lever is centrally fulcrumed and is adapted to be swung between three positions, the central position being neutral and serving to disengage both the power clutch and the brake, while the extreme positions cause the engagement of one or the other. It will thus be seen that by moving the lever 30 at suitable times the power may be thrown off and the brake applied, and subsequently the brake disengaged.

The movements of the lever 30 may be effected partly at the will of the operator through a starting lever or the like. Thus, a short link 31 is shown as extending between lever 30 and swinging arm 32, the

link and arm forming a toggle by which the lever may be swung. A link 33 extends from the toggle joint to a control lever or pedal 34, which is provided with a foot piece 35 at its front end, having different operative positions, as seen in Fig. 6.

The bottom pedal position 34^a corresponds with the full driving condition of the machine, and the pedal is held down in that position during the normal running. In the lifting of the pedal from its bottom to its top position, the first action is the disengagement of the power clutch, which may occur at or about the pedal position 34^b. The next pedal position 34^c is the middle or neutral position in which neither the power clutch nor the brake are engaged. At 34^d the brake commences to engage, and at 34^e it is in full engagement.

The pedal lever is fulcrumed at 36 and is provided with a lifting spring 37, which is strong enough to put the brake into full effect.

The operator by depressing the pedal at will to its lowest position puts the power drive into effect upon starting the machine. When he desires to stop, he releases the pedal, thus disengaging the power, and the pedal moving to its topmost position causes the engagement of the brake. The remainder of the stopping action is automatically controlled or effected by the machine without the attention or skill of the operator; although the operator may lift the pedal to its halfway position and there latch it by hook 38, upon which the shaft is left free to run down and stop by natural causes.

The preferred automatic operation of the mechanism after the pedal has been let fully up is that, through the governor referred to, the pedal is thrown down to its neutral position so as to disengage the brake, leaving the shaft running at the designated slow speed. Up to this time the mechanism has prevented the stop device from acting, but at this time permits it to act, so that the shaft, now running under harmless momentum, is brought to a full stop without shock and in the desired final angular position.

The stop device may consist of a rotating disk 39, turning with the cross shaft 14 and having a stop projection combined with a non-rotatable stop or dog 56. These parts are shown prior to their stopped position in Fig. 5, and in their stopped position in Figs. 4 and 2.

The further details and the control of the stop device will now be explained.

The disk 39, which acts both as a rotating stop projection and as a guard, is shown slidable axially upon a squared portion of the cross shaft 14. This enables the disk to be shifted to the left, where it will be inoperative, or to return to the right, as seen in Fig. 6.

Fig. 2, where it becomes effective, being directly above the dog 56.

For shifting the disk 39 it may be provided with a grooved collar 40 engaged by studs at the end of an upright yoke arm 41, which forms part of a plural-armed lever, another arm 42 of which extends to the left. This lever is fulcrumed on a fixed bracket 43 secured to the frame of the machine.

Beneath the extremity of arm 42 and pivoted thereto is a slide or plunger 44, fitted at its lower end to move up and down within a portion of the fixed bracket 43. A spring 45, bearing on the bracket and plunger, tends to lift the latter and thereby force the stop disk 39 toward its effective position.

When the plunger is moved down in starting the machine and the stop disk moved to the left, the parts are adapted to be temporarily locked in this position by means of locking shoulders 47 on the plunger and 48 on a bolt 49, as seen in Fig. 3. A spring 50 presses the bolt to normally cause the shoulders to engage. As will be afterward explained, this locking device is adapted to be unlocked at the proper instant by means of the governor, so as to permit the stop device to become effective.

The stop pin or dog 56 is directly below the effective position of the disk 39 and is slidably mounted in the bracket 43, having a spring 57 tending to lift it. The stop pin has an adjustable stop 58 limiting its upward movement.

Referring to the contour of the stop disk 39, it is shown as constructed with a deep recess or depression 61, which is followed by a guard or concentric portion 62, this in turn being followed by a rising portion 63, and lastly a final stop shoulder 64.

It will be understood that in the normal running of the machine the stop pin 56 stands to the right of the disk in Fig. 2, so that the stop device is ineffective, and the pin will then also stand in its highest position, as indicated in Fig. 5. This condition continues as long as the operator holds the pedal at its lowest position. A loose link 55 will be noticed on Figs. 1 and 2, whereby, when the pedal is fully depressed, it draws down the arm 42 and the plunger 44 until the latter is locked by the engagement of the shoulders 47, 48. When the operator releases the pedal, it springs to its highest position, thus throwing out the power drive and engaging the retarding clutch 19, 27. The shaft is thereupon promptly slowed down until a governor 70 comes into play to control the further action of the stop mechanism.

The governor 70 for convenience is illustrated of the centrifugal ball type, being mounted on a vertical shaft 71 geared by helical gears 72 and 73 with the driven shaft 74 so that the governor operates in syn-

chronism with the parts to be stopped. In this type of governor the balls assume positions farther or nearer to the axis according to their speed and centrifugal force. The out-throw of the balls operates through links to lift a collar 74 against the resistance of a spring. The collar 74 thereby moves up and down on the vertical shaft, having a predetermined vertical position corresponding with each degree of speed of the machine. When the machine is running at full speed, the sleeve 74 is elevated, but as the machine is slowed down by the braking device 19, 27, the sleeve gradually descends.

Connections are employed such that, when the sleeve descends to a position corresponding with the predetermined slow speed of the shaft, the stopping device 39, 56 is permitted to operate. Thus, the collar 74 is grooved and is engaged by studs on a yoke arm 75. This arm is pivoted to a fixed bracket and has a downward arm 76, which is connected by link or pusher 77 to the vertical lever 78, the lower end of which extends into engagement with a recess or socket in the locking bolt 49. The operative relation between the link 77 and the lever 78 may be adjusted by lock nuts 79. In this way the governor operates when the shaft speed is reduced to the desired quantity to throw the locking bolt 49 to the left, thus releasing the plunger 44, which is lifted by its spring 45 so as to throw the stop disk 39 into effective position.

In this way the object is attained of preventing the stopping device from acting until the shaft's speed is down to a designated point, and is then permitted to operate to stop the shaft in the desired angular position without substantial shock. The final impact does not occur immediately upon the unlocking of the plunger 44, since the stop disk 39 must wait until it reaches the Fig. 5 position before it can shift axially into effective position. Thereafter the disk turns while the stop pin 56 rides around the portions 62 and 63 of the disk until the final impact of the shoulder 64 against the stop pin illustrated in Fig. 4.

When the braking device 19, 27 is employed, this, if left in engagement, might, owing to the great uncertainty of brake action, prematurely stop the shaft before the parts have reached the desired final position indicated. Therefore it is a part of this invention that the governor 70 shall disengage the brake when the shaft speed has been reduced to a designated point at which the speed is high enough to carry the parts through to the final impact, but insufficiently high to produce objectionable shock.

This throwing-out of the braking device by the governor is shown as effected herein by connections including an arm 81 rigid with the arms 41 and 42; the arm 81 con-

5 nected by a link or push rod 82 and an adjustable head 83 to the control lever or pedal 34. When the plunger is released and the parts jumped to the position shown in Fig. 2, the rod 82 thrusts the control lever 34 downwardly from its topmost to its neutral position, marked 34^e in Fig. 6. This in turn 10 adjusts the double clutch 25 to its neutral position, and the retarding force is thereby removed, leaving the shaft to rotate under low momentum until the final stoppage by the stopping device 39, 56.

15 It will thus be seen that I have described a driving and stopping mechanism embodying the principles of this invention, and attaining its objects and advantages. Since many matters of arrangement, design, detail and other features may be modified without departing from the novel principles involved, it is not intended to restrict the invention to such features, except so far as set forth in the appended claims.

20 What is claimed is:

1. The combination with the rotating parts of a machine, of a retarding device for slowing the rotary speed thereof, a speed operated governor, and connections from said governor for rendering the retarding device inoperative at a predetermined speed.
2. A stop mechanism comprising in combination with the rotating parts to be stopped, a stopping device, a retarding de-

vice for slowing the speed of the rotary parts, a speed operated governor, and connections from said governor for rendering the retarding device inoperative at a predetermined speed, and causing the stopping device to become effective.

3. A stop mechanism comprising in combination with the rotating parts to be stopped, a stopping device, a retarding device for slowing the speed of the rotary parts, means for holding inoperative the stopping device, a governor, and connections whereby the governor at a predetermined speed renders the retarding device inoperative and releases said holding means, whereby the parts may be stopped from slow speed by said stopping device.

4. A stop mechanism comprising in combination with the rotating parts to be stopped, a stopping device, a retarding device for slowing the speed of the rotary parts, a driving means, a lever shiftable from a first to a second position for disengaging the driving means and applying the retarding device, and a governor operative at a predetermined speed for throwing said lever to a third position for disengaging the retarding means prior to the action of said stopping device.

5. In testimony whereof, I have affixed my signature hereto.

JOHN REECE.
